(57) **CLAIM**

The ornamental design for a display screen or a portion thereof with graphical user interface, as shown and described.

DESCRIPTION

FIG. 1 shows a display screen or portion thereof with graphical user interface detailing our new design according to an embodiment of the present invention; and, FIG. 2 shows a display screen or portion thereof with graphical user interface detailing our new design according to an alternative embodiment of the present invention. The broken line showing of a display screen or portion thereof with graphical user interface is included for the purpose of illustrating portions of the article and forms no part of the claimed design.

1 Claim, 2 Drawing Sheets
